UNITED STATES PATENT OFFICE.

WILLIAM E. S. STRONG, OF DETROIT, MICHIGAN, ASSIGNOR TO THE WINKLEY COMPANY, OF HARTFORD, CONNECTICUT, A CORPORATION OF CONNECTICUT.

FILLING APPARATUS.

SPECIFICATION forming part of Letters Patent No. 792,857, dated June 20, 1905.

Application filed September 26, 1901. Serial No. 76,486.

To all whom it may concern:

Be it known that I, WILLIAM E. S. STRONG, a citizen of the United States of America, and a resident of Detroit, in the county of Wayne 5 and State of Michigan, have invented certain new and useful Improvements in Filling Apparatus, of which the following is a specification.

This invention relates to improved means 10 for filling vessels of various kinds with liquid from a barrel or tank or other source of supply, the object of the invention being to provide improved means for filling such vessels expeditiously without allowing them to overflow and without otherwise wasting the liquid, 15 also to provide means for returning the drippings to the barrel or receptacle.

A further object of the invention is to provide efficient and convenient means for pumping 20 the liquid from a barrel or tank and to adapt the pumping devices to different depths, so that it may be readily applied to barrels or tanks which differ in depth to a considerable extent.

25 This invention is herein illustrated as being embodied in a device for filling oil-cans, being shown as applied to an ordinary barrel.

Figure 1 of the drawings is a side elevation in section taken through the longitudinal 30 center of the apparatus and of the barrel to which it is applied. Only a small portion of the barrel is herein shown, enough to enable the method of attachment and relation of this apparatus thereto to be understood. Fig. 2

35 is a plan view of the apparatus of Fig. 1. Fig. 3 is a plan view in section taken on line 3 3 of Fig. 1. Figs. 4, 5, and 6 are fragmentary views in section, taken on the line 4 6 of Fig. 1, showing the different positions of 40 the three-way valve.

The principal frame for supporting the parts of this apparatus consists of a goose-neck column 8, having a flanged base 9, which may be sufficiently wide to insure a proper 45 stability of the apparatus when mounted upon a barrel or tank, or it may be attached thereto by means of screws 11. The bottom of the base is preferably provided with a boss 12

for extending into the bung-hole of the barrel to centralize the apparatus therewith and 50 to conduct the drip below the surface of the barrel-head. The column is adapted to receive an extensible tubular connection for the pump, also to receive an overflow-tube, both of which will be hereinafter more fully described. The body of the column is provided with vertical ways 14 for receiving the vertical sliding bracket 15, the latter, as best 55 shown in Fig. 3, being clamped together upon opposite sides of the ways by means of the thumb-screw 16, so as to fix the bracket at any desired height. Upon the bracket 15 is mounted a platen 18, which is mounted for vertical movement upon the bracket, being raised and lowered by means of the lever 19, 60 pivotally mounted upon the bushing 20, and being retained in position by means of the head of the thumb-screw 16, while permitting the lever to turn freely upon the stud.

In order to enable the oil that may drip upon 70 the platen to be conducted back to the barrel or tank, the stem 21 of the platen is made hollow, the upper surface of the platen being slightly concave, so that the drip will flow toward and through the hollow stem and into 75 the conductor 22, which extends outwardly from the base. The edges of this conductor are turned upwardly and the bottom is inclined, as shown in Fig. 1, toward its outlet 23, through which the drip finds its way back 80 into the barrel or tank.

The pump-barrel 26 is connected with the lower end of the column 8 by means of the tubular sleeve 27, one end of which is threaded into the top of the barrel, while the other is 85 threaded into the base of the column. The lower end of the pump-barrel is provided with a check-valve, which is preferably a ball 28. The plunger 30 of the pump, which may be of any approved construction, is herein shown to 90 be provided with a cupped packing 31 and with a lifting-valve 32. The stem 33 of this plunger is provided on one side with a longitudinal slot or opening into which a screw or key 95 extends, which prevents the plunger from turning, while permitting of its longitudinal

movement. The upper end of the stem 33 is threaded to receive the extension-rod 36 of the pump, which extends upwardly through the sleeve 27 inside of the column 8 and passes out 5 at the upper end of the column through a stuffing-box formed by the gland 37 and is provided at its upper end with a suitable handle 38. By the operations of the pump the oil is forced upwardly through the sleeve 27 into 10 the cavity 39 of the hollow column 8, which is curved or "goosenecked" forward, as shown in Fig. 1, terminating in a hub 42, in which is seated the combined three-way cock and valve-plug 43. The passage 45 of the column conducts the oil from the cavity 39 to the combined filling nozzle and valve, which is provided with two independent passages 44 and 15 46, the first of which when the valve is in the position shown in Figs. 1 and 4 leads downwardly into the oil-can 48, while the other passage 46 communicates when the valve is in the position shown in Fig. 6 with a projecting spout 50 at the front side of the hub 42, which may be employed for filling larger cans or in 20 connection with a flexible tube may be utilized for forcing the oil to some other tank or receiver or receptacle. Thus by turning the valve to the positions shown in Figs. 4 or 6 the supply of oil may be forced by the pump 25 either into the can 48 or through the spout 50, and by turning the valve to the position shown in Fig. 5 the passage-way 45 is closed entirely, so as to prevent the flow of oil therefrom. The valve is preferably seated in a conical or 30 tapering bore of the hub 42 in the usual way and is prevented from being inadvertently withdrawn, while permitting it to turn freely, by means of the screw 51, which projects into a peripheral groove of the valve.

35 The lower end of the hub 42 is preferably provided with a packing-ring 53, against which the mouth of the can is forced by the pressure of the lever 19 to prevent the overflow of oil upon the outside of the can. As a means 40 for conducting the overflow of the oil back into the barrel or other source of supply the valve is provided with an annular passage 55, leading to a port 56, which extends through the side wall of the valve into coincidence 45 with the overflow-tube 57 when the valve is in the position shown in Figs. 1 and 4, which is the only position in which a provision for overflow is required. A convenient way of 50 providing the annular passage 55 is illustrated 55 in Fig. 1, wherein the vertical portion of the inlet-passage 44 is a tube 47, which is driven into its seat in the upper portion of the valve 43, the lower portion of the valve being counterbored to a size sufficiently larger than the 55 tube to provide a suitable area for the overflow of the oil to the port 56. This port is located below the plane of the lateral passages 44, 45, and 46, and therefore does not interfere with them or communicate with them excepting by way of the lower end of the tube 60 65

47. The overflow-tube 57 extends inside of the column and preferably in a cored recess 58 thereof, as shown in Figs. 1 and 4, passing at its lower end through the hub or boss 12 into communication with the barrel or receptacle from which the oil is withdrawn. 70

In order to enable the oil-cup to be filled with certainty to a definite and convenient height without any care or observation on the part of the operator, the lower ends of the 75 valve 43 and of its tube 47 are extended below the packing-ring 53 to a point coincident with the desired level of the oil in the can below the mouth thereof, so that the annular passage 55 forms a siphon through which the 80 oil is reduced to that level when the pump is stopped and before removing the can. This particular feature is an improvement upon the corresponding device of United States Patent No. 463,088, of November 10, 1891, in 85 the respect that the overflow-passage is controlled by the valve and may, as herein shown, be closed thereby when the valve is turned away from the position shown in Figs. 1 and 4, and this may be desirable in the case of 90 highly-volatile fluids. This overflow-passage may also serve as a vent, inasmuch as the air displaced from the can will displace a corresponding amount of oil in the barrel. If it is desired to utilize this overflow-tube as a 95 vent when forcing oil through the spout 50, this may be accomplished by providing an additional passage 60, (see Figs. 5 and 6,) leading from the tube 47 to the overflow-tube 57 when the valve is in the position shown in 100 Fig. 6.

In order to enable the pump-barrel and its plunger to be readily adjusted to suit different depths of barrels, tanks, or other receptacles from which the oil is to be withdrawn, the 105 sleeve 27 is provided with a screw-thread for a distance equaling the amount of the desired extension or adjustment, that thread fitting a correspondingly-threaded hole in the lower end of the column, being fixed in its adjusted 110 position by means of the check-nut 62, so that by loosening the check-nut the sleeve 27 and its attached barrel 26 may be adjusted to the desired depth. In order to make a corresponding and simultaneous adjustment or extension of the barrel and of the connection 115 between the pump-handle 38 and the plunger 30, so as to maintain it in proper operative relation, the extension-rod 36 is threaded into the upper end of the plunger-stem 33, employing a screw-thread which is equal in pitch to the thread of the upper end of the sleeve 27. As the pump-barrel, with its sleeve 27, is screwed up or down with relation to the 120 column the plunger 30 and its stem 33 are 125 carried with the barrel by means of the screw 35, so that by holding the extension-rod 36 from turning by means of its handle 38 while the barrel, with its sleeve 27, is being adjusted with relation to the column a correspond- 130

ing adjustment takes place between the extension-rod and the plunger.

The operation of this device will be understood from the preceding description and is, briefly stated, as follows: Having ascertained the depth of the barrel from which the liquid is to be withdrawn, the barrel is adjusted to a corresponding depth by loosening the check-nut 62, holding the handle 38, and screwing the barrel up or down, as the case may be, to the desired point. The adjustment of the plunger upon its rod 36 is coextensive with that of the sleeve 27 with relation to the column, as above described, by virtue of the fact that their respective adjusting-screws are of the same pitch. Having established this adjustment of the pump-barrel, it is fixed in position by means of the check-nut 62, and the apparatus is then seated upon the top of the barrel or tank, as shown in Fig. 1, the cup or other vessel to be filled is placed upon the platen, as shown in Fig. 1, the valve is turned to the position shown in that figure, and the pump is worked, by means of its handle 38, until the operator is satisfied that the cup is overflowing, which is readily ascertained by brief experience. He then ceases to operate the pump and waits a moment for the siphon to take effect, so as to reduce the level to a point which permits of the insertion of the cap, plug, or nozzle of the can. The bracket 15 should be adjusted to a height which is convenient for the cups which have to be filled, the stroke of the lever 19 and its platen 35 18 being sufficient to allow for a considerable variation in the heights of the cups.

This combined filling attachment and pump is a compact and substantial adjunct for stores, factories, and general use and is adapted to withstand the severe usage to which such appliances are frequently subjected. The working parts, pipes, &c., which in analogous devices are usually exposed to a greater or less extent, are herein protected by a strong and substantial casing, preferably of cast-iron, which will withstand falls and blows that would be liable to bend or destroy the ordinary exposed pipes of tin or brass. Moreover, being a self-contained unitary article the parts are not liable to become separated or mislaid or lost, and it may be transferred in its entirety from one barrel or tank to another.

The overflow-tube 57 may be of lead or any other material having sufficient flexibility to enable it to follow the curve of the goose-necked column, and the upper end or both ends of the tube may be secured in position by expanding the tube in its seat or in any other well-known way. Instead of the overflow-tube an independent overflow-passage may be cored in the metal of the column itself, and in various other ways which will suggest themselves to users and constructors

of this class of machinery the embodiment 65 herein shown may be modified to suit considerations of economy or to suit the conditions of particular cases.

I claim as my invention—

1. In a filling apparatus, the combination 70 of a filling-nozzle, an adjustable bracket, a can-supporting platen mounted upon the bracket for longitudinal movement in a straight line toward and from the nozzle, and a lever pivoted on the bracket for imparting 75 the longitudinal movement of the platen.

2. The combination in a filling or discharge apparatus provided with a supply-passage, and with an overflow-passage, of a valve-plug mounted for turning movement and forming 80 a discharge-nozzle having discharge and return passages which communicate with the supply-passage and the overflow-passage, respectively, at one position of the valve-plug, and are closed at another position of the plug. 85

3. The combination in a filling or discharge apparatus, provided with a supply-passage, and an overflow-passage, of a valve-plug mounted for turning movement and having 90 independent passages extending to the discharging portion of the plug, and communicating with the said supply and overflow passages, respectively at one position of the plug and being shut off from said communication at another position of the plug. 95

4. The combination in a filling or discharge apparatus, of a supply-passage, a valve-plug mounted for turning movement and having independent passages leading to different points of discharge, the said passages being 100 brought into communication with said supply-passage at different times by the turning movement of the plug.

5. The combination in a filling or discharge apparatus, of a supply-passage, and an overflow-passage, a valve-plug mounted for turning movement, and provided with independent passages leading to different points of discharge, the said discharge-passages being 105 brought into communication with the said supply-passage at different times by the turning movement of the plug, the plug being also provided with a vent-opening connecting one of said discharge-passages with the overflow-passage when the other discharge-passage is 110 in communication with the supply-passage. 115

6. In a filling apparatus, the combination of a filling-nozzle, a reciprocating platen for raising and lowering a can to and from the nozzle, adapted to collect the drip, and a conductor for receiving the drip from the platen and returning it through the apparatus to the tank or source of supply. 120

7. In a filling apparatus, the combination of a rigid supporting-column having a supporting-base and a projection for extending into the bung-hole or outlet-aperture of the tank or source of supply, a filling-nozzle, a supply-

passage, and an overflow-passage inclosed in the column and communicating between the base of the column and the filling-nozzle.

8. The combination with filling apparatus, of a rigid column inclosing a supply-passage, a nozzle connected therewith and a separate overflow-passage inclosed by said column for the return of the liquid from the nozzle.

9. In a filling apparatus, the combination of 10 a rigid column containing separate supply and overflow passages, and a combined valve-plug and filling-nozzle communicating with and controlling both passages, a platen for supporting the oil-can and for collecting the drip, 15 and means for returning the said drip through the column.

10. The combination with filling apparatus, of an extensible pump-barrel and plunger-rod, both provided with screw-threads of the same 20 pitch for simultaneous and equal adjustment.

11. In combination with a filling apparatus, an extensible pump-barrel connected with the apparatus by means of a threaded extension, and a plunger-rod connected with the pump- 25 plunger by means of a thread of substantially the same pitch as that of the pump-barrel, whereby the barrel and the plunger may be extended equally and simultaneously.

12. In combination with a filling attachment, an extensible pump therefor, comprising 30 a barrel having a threaded extension fitting the apparatus, a plunger provided with an extension-rod fitted thereto with a screw-thread of a pitch substantially equaling that of the barrel extension, with means, as a key, for 35 causing the pump-plunger to turn with the barrel, whereby the plunger may be extended simultaneously and equally with the barrel as the latter is unscrewed from the apparatus.

13. In a filling apparatus, the combination 40 of a column for supporting a can and conducting the liquid thereto, an extensible pump attachment comprising a pump-barrel having a threaded extension fitting the column, a plunger, and an extension-rod connected with the 45 plunger by means of a screw-thread of a pitch substantially equaling that of the barrel extension, whereby the pump-barrel and its plunger may be extended equally and simultaneously. 50

Signed at Hartford this 9th day of September, 1901.

WILLIAM E. S. STRONG.
